UNITED STATES PATENT OFFICE.

JOHN J. DU BOIS, OF DETROIT, MICHIGAN.

ERASER-REEL.

1,299,921.

Specification of Letters Patent. Patented Apr. 8, 1919.

Application filed August 16, 1918. Serial No. 250,182.

To all whom it may concern:

Be it known that I, JOHN J. DU BOIS, a citizen of the United States, residing at Detroit, in the county of Wayne and State of Michigan, have invented new and useful Improvements in Eraser-Reels, of which the following is a specification.

The present invention aims in providing a novel construction of eraser attachment for typewriting machines designed for attachment to the typewriter in such a manner whereby the operator may conveniently make erasures in an expeditious manner and prevent any unnecessary loss of time.

15 The primary object of the invention resides in the production of a device of the above stated character, which is simple in construction, durable and efficient in use, and one which may be quickly and easily re-20 paired, and manufactured and sold at a minimum cost.

25 A still further object of the invention is the provision of a frame of novel construction adapted for supporting therein the reel on which is automatically wound the flexible eraser connector.

30 A still further object of the invention resides in the provision of means whereby the reel is operatively connected or associated with the spindle.

35 With the above and other objects in view, the invention consists in the novel features, details of construction and combination of parts which will hereinafter be more fully set forth, illustrated in the accompanying drawing and pointed out in the appended claims.

In the drawing:

40 Figure 1 is a perspective view of a portion of typewriter showing the device attached thereto for use;

Fig. 2 is a longitudinal sectional view taken through the attachment;

45 Fig. 3 is a perspective view of the frame removed from the casing;

Fig. 4 is a side elevation of the reel, illustrating the manner of connection of the spindle therein; and

50 Fig. 5 is a plan view of the device assembled for use.

Referring more particularly to the accompanying drawing, the eraser attachment here denoted by the character 5, for clearness in its operation is shown as attached to the 55 frame A of a typewriter machine. The attachment in its entirety, comprises a cylind-

rical hollow casing, preferably constructed of aluminum, metal or the like material, denoted by the character 6, provided with opposite open ends 7. Encircling the casing at 60 a point adjacent the open end 7 thereof is formed a beading 8 adapted to engage in the ridge 9 of a cap 10. Each of the caps 10, like the casing, is preferably constructed of aluminum or the like material, and is stamped 65 out to provide pairs of diametrically disposed tongues 11, which, upon the assembling of the caps to the casing, will project inferiorly of the casing and at substantially right angles to the cover, the purpose of 70 which will be hereinafter more fully set forth as the description of the invention is proceeded with. The removable engagement of the caps with the open ends of the casing facilitates the insertion therein of a resilient 75 substantially U-shaped frame 12, comprising a connecting portion 13 and spaced limbs 14. Each of the limbs is terminally bent in confronting relation one to the other to provide guides 15. Upon the assembling of the frame 80 within the casing, the tongues 11 of one cap 10 are first bent around one of the limbs at points adjacent the upper and base portions thereof, the cap thence is shoved onto the casing and the tongues 11 of the other of said 85 caps are likewise secured in embracing relation to the other of said limbs, establishing a detachable and rigid connection of the frame within said casing. As clearly illustrated in the detail view of the frame, each 90 of the limbs 14 of the frame 12 is bent at an intermediate point inwardly in line with the connecting portion 13, to provide on the exterior of the limbs a substantially V-shaped bearing or notch 16. In order to simplify 95 the construction of a device of this character and to reduce the cost of manufacture to a minimum, I employ a flexible spindle 17, here illustrated of substantially looped formation, disposed lengthwise with respect to the frame 100 and casing, with the crown ends 18 thereof frictionally engaging in the bearings or notches 16 of the frame. Journaled on the spindle 17 is a reel 19 of spool formation, and keyed or otherwise suitably secured to the 105 flexible spindle by the insertion of a pin 20 through a transverse opening 21 of the reel. The opening 21 intersects the longitudinal bore 22 of the reel. Wound upon the periphery of the drum 19 is a flexible connector 23 110 provided on its free end with a suitable fastener, denoted by the character 24 adapted to

engage in the eraser 25 and establish a connection of the eraser with the attachment, to permit the connector to be automatically rewound on the drum when the use of the 5 eraser is no longer desired. Suitably secured to one of the caps 10 is an attaching member 26, here shown in the form of a clip, adapted to be fastened to the frame A of the machine through the employment of a thumb screw 27.

10 From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I desire to have it understood that the device shown is 15 merely illustrative and that such changes may be made when desired as are within the scope of the appended claims.

Having thus described the invention, what is claimed as new, is:—

- 25 1. An eraser attachment for typewriting machines comprising a casing having open ends, caps for closing the open ends of the casing, a frame mounted in said casing, means carried by the caps and co-acting with 30 the frame for preventing any loose movement of the latter with respect to said casing, a spindle mounted on said frame, a reel keyed to said spindle, and means for connecting an eraser with said reel.

2. An eraser attachment for typewriting 35 machines, comprising a casing having open ends, caps for closing the open ends of the casing, a frame having notched limbs mounted in said casing, means carried by the cap and coacting with the notched limbs of the 40 frame for preventing any loose movement of the latter with respect to said casing, a flexible spindle mounted in the notched limbs of the frame, a reel keyed to said spindle, and means for connecting an eraser with 45 said reel.

3. An eraser attachment for typewriting machines, embodying a casing provided with opposite open ends, means for closing the open ends of said casing, a reel mounted in said casing, and diametrically disposed means formed integral with the closing means and co-operating with the reel for preventing any loose movement of the latter with respect to said casing. 50

4. An eraser attachment for typewriting machines, embodying a casing having open ends, caps for closing the open ends of said casing, means carried by said cap and having engagement with the limb portions of 60 the frame for detachably connecting the latter in said casing, a spindle mounted in the limbs of said frame, a reel keyed to said spindle, and means carried by the reel for connecting therewith an eraser. 65

In testimony whereof I affix my signature.

JOHN J. DU BOIS.
